WINDER GUARD

Henry R. Patterson, Jr., West Chester, Pa., and Robert C. Walker, Wilmington, Del., assignors to Beloit Eastern Corporation, Downingtown, Pa., a corporation of Delaware

Filed Sept. 26, 1961, Ser. No. 140,743
4 Claims. (Cl. 242—66)

The present invention relates to improvements in winder machines and particularly to an improved guard for protecting the nip of the winder and for moving the guard as the diameter of a wound roll changes.

In a winder machine such as for winding a paper web on a roll, the roll is supported on a pair of winder drums with the web being wound on a core to form the wound roll. A nip is formed between the roll and winder drum on the down travelling side of the roll which is dangerous to operating personnel in that an article of clothing or their hand may be drawn into the nip with very disastrous results. The outer surface of the wound roll travels at a very high speed such as on the order of 7,500 feet per minute and it is easy for the hand of an operator to be drawn into the unprotected nip. The wound rolls reach substantial weights and may weigh as much as over 2,000 pounds so that a crushing pressure exists in the nip which will dismember an individual who may be accidentally caught therein. As the wound roll builds up in size it can easily brush against an individual near the nip, and the change in position of the surface of the roll as it increases in diameter makes it difficult to protect the nip.

An object of the present invention is to provide an improved method and apparatus for guarding the nip and the surface of a wound roll at the nip of a high speed winding machine wherein the surface and the exact position of the nip change during operation due to build up or change in diameter of the wound roll during operation.

A further object of the invention is to provide an improved nip guarding device for a high speed winding machine wherein a guard is controllably positioned by being moved during operation of the machine in accordance with the change in diameter of the wound roll so that the guard will be maintained in close guarding relationship to the moving surface of the wound roll.

A still further object of the invention is to provide an improved nip guard for a winding machine including a pivotally mounted guard beam which is supported so that it will remain parallel to the surface of the wound roll, to provide means for accurately detecting change in position of the surface of the roll with its increase in diameter, and to provide a signal which is a function of surface position for controlling and moving the location of a guard relative to the winding nip so that the nip will receive optimum protection.

Other objects, advantages and features will become more apparent with the teaching of the principles of the invention in connection with the disclosure of the preferred embodiment thereof in the specification, claims and drawings in which:

FIGURE 1 is a side elevational view of a winding machine shown somewhat in schematic form and being pro-

2

vided with a nip guard in accordance with the principles of the present invention;

FIGURE 2 is a side elevational view of the lower portion of the machine of FIGURE 1 showing the position of the nip guard when the roll is just starting to be wound; and

FIGURE 3 is a somewhat diagrammatic illustration of control mechanism for positioning the nip guard during operation.

As shown on the drawings:

FIGURES 1 and 2 show a paper winder having a pair of spaced parallel horizontal winder drums 10 and 11 which are mounted on a frame 12 supported on a floor surface 13. The winder drums 10 and 11 carry a winding roll 14 thereon and may be driven in rotation by suitable mechanism, not shown, for this purpose.

A paper web W is wound on the roll 14 and is supplied from a suitable source travelling over a guide roll 15 and up over the winder drum 11 onto the outer surface 20 of the roll 14.

The roll 14 of course starts as a small roll with the lead end of the paper being started on a core, and builds up in diameter, with FIGURE 2 showing the roll 14 at a smaller size and FIGURE 1 showing the roll as it is 25 being completed. A rider roll 16 may rest on the top of the roll to stabilize it in the winder drums 10 and 11 and increase frictional contact of the roll with the surfaces of the drums 10 and 11. The rider roll is supported on a hanger 17 which is suitably guided in the frame and 30 the weight of the rider roll and its hanger are in part supported from above on a cable 18 passing up over guide sheaves 19 and 20 and the cable is counterweighted by a weight, not shown, in the direction indicated by the arrow 21. A fresh core 23 for winding a new roll is 35 suitably supported in a rack 22 which need not be described in detail since it forms no part of the present invention.

The lead winder nip is shown at N with the surface of the roll 14 travelling in the direction indicated by the 40 arrowed line. The nip is protected by a guard member 24 in the form of an elongated guard beam which extends across a head of the nip N. A pivotal roll-out board 27 is shown supported on the frame and resting on top of the guard beam 24 with a ridge 28 on top of the beam 45 so that the beam slides beneath the roll-out board 27 as the beam 24 is moved.

The guard beam is supported on arms 29 at its ends for pivotal movement toward or away from the outer surface 31 of the roll 14, and it is controllably positioned 50 by being drawn away from the center of the roll 14 as its diameter increases, by pneumatic support cylinders 25 and 26 having pistons attached to piston rods 25a and 26a connected to the ends of the beam 24 and being synchronized so that the beam will receive equal support 55 at each end and will not twist so that a small clearance space can be maintained between the leading edge 30 of the beam and the outer surface 31 of the roll 14. It will be recognized that optimum protection is obtained by maintaining the clearance space between the edge 30 of the beam and the surface 31 at a minimum, although the beam must not engage the paper inasmuch as at the high surface speeds this would tear or score the paper and damage its surface.

The guard beam 24 is positioned as a function of the

change in diameter of the roll, or in other words as a change in position of the outer surface 31 of the roll 14. The guard beam is moved during winding of the roll so as to be maintained in close guarding proximity thereto. To operate the pneumatic cylinders 25 and 26 to maintain the accurate guarding position of the beam 24, the displacement or increase in diameter or radius of the winding roll is sensed and converted to a displacement signal, the displacement signal is converted to a control signal which is a function of the output of the pneumatic cylinders 25 and 26 which is necessary to obtain the proper and accurate position of the guard beam 24. As shown in FIGURE 1, the core 32 of the winding roll 14 has a connector 33 rotatably attached to its end and the connector is attached to a cable 34 which passes over the top of a cam sheave 35 and the cable has a weight 39 at its end which maintains its tension over the sheave. An idler sheave 40 increases the angle of wrap of the cable. To the sheave 35 is attached a control cam 36 which engages a control arm 37 operating a control signal valve 38. The valve 38, as also shown in FIGURE 3, produces an output pressure signal for operating the air cylinders 25 and 26.

An air supply source such as the type available in shops having paper making and winding machinery is provided, as shown schematically by a pump 48 and the air flows through a filter 41 with the operating air flowing through a branch line 42 and the signal air flowing through a branch line 45. The operating air flows through an adjustable pressure regulator 43 to the air cylinders 25 and 26 and a gauge 44 is connected to register operating supply air pressure.

The signal air pressure in line 45 flows through an adjustable pressure regulator 46 to the signal valve 38 and a gauge 47 is connected to read the pressure of the air to the control valve 38.

A valve 49 is interposed in line 50 leading from the signal pressure regulating valve 38 to the air cylinders, and the valve 49 is solenoid operated and deactuates the control system when the solenoid valve is deenergized. A switch 51 is moved to the dotted line closed circuit position for actuating the automatic system, and is turned to the solid line position for deactuating the automatic system for manual operation, such as may be done when the guard beam is to be moved out of the way for threading. A switch 52 may be a selector switch interlocked to the main drive switch to place the system in operation during normal winding. The switches are connected between electrical lines shown at L₁ and L₂ which supply the solenoid valve 49.

The air cylinders 25 and 26 in their entirety are follow up or servo units which provide accurate positioning of the piston rods 25a and 26a in accordance with the pressure signal provided by the valve 38. Various types of servo output members may be employed operating from a signal, and a mechanism well adapted for use in the present system is a pneumatic positioner sold commercially by the Conoflow Corporation as a Cylinder Conomotor.

The shape of the control cam 36 is easily determined by laying out or plotting the positions of the point of connection 25b between the piston rod 25a and the guard beam 24 (which is the linear displacement of the piston rod 25a) against the vertical displacement of the core 32 of the roll. Since the cam 36 is driven in rotation directly by vertical displacement of the core, the surface of the cam 36 will be plotted to give the required displacement of point 25b to obtain the proper position for the guard beam 24 for all roll diameters. In other words, as will be appreciated from the above by those skilled in the art, the cam has a shape to produce a control pressure signal to operate the cylinders to maintain the beam 24 in close guarding position as the roll builds up in size.

It is to be understood that while the preferred ar-

rangement is illustrated, the position of the guard beam 24 could be more directly controlled such as by a surface responsive air jet control or an electric eye control, both of which would maintain the guard beam in close guarding proximity to the surface 31 of the roll without touching the surface. Also, servo motors such as the above described Cylinder Conomotor of the integral type or the external type positioning device are well known to the art and need not be described in detail.

It is to be further understood that while the mechanism is shown and described as being advantageous in a paper roll winding machine, it may be employed in other winding machine environments wherein the diameter of a wound roll changes, and may also be employed to guard the nip of a roll as it is unwound, and the term "winding machine" is used to indicate machines used for winding or for unwinding purposes.

In operation, a roll 14 begins winding with the outer surface 31 adjacent the nip, and the nip, being guarded by the guard beam 24. As the diameter of the roll 14 builds up to be larger, as shown in FIGURE 1, the core 32 rises and the cam 36 is rotated to operate the signal control valve 38, and the pressure signal in the line 50 operates the servo air cylinders 25 and 26 to position the guard beam 24 maintaining its leading edge 30 in close proximity to the outer surface 31 without touching the surface. Thus, the nip N is guarded equally as well for all stages of operation of the winding of the roll 14.

The drawings and specification present a detailed disclosure of the preferred embodiments of the invention, and it is to be understood that the invention is not limited to the specific forms disclosed, but covers all modifications, changes and alternative constructions and methods falling within the scope of the principles taught by the invention.

We claim as our invention:

1. In a winding machine having a winder drum for engaging a roll with a web being wound thereon, a guard beam extending along the roll ahead of the drum, a pneumatic cylinder for positioning the guard beam relative to the roll surface, said cylinder operated by a pressure signal, a control valve for providing said pressure signal, a rotary cam for operating said control valve, a sheave connected to the cam, and a weighted cable threaded over said sheave and connected at one end to the center of the roll with said cam having a shape to provide a control pressure signal for maintaining the beam in close proximate guarding relation to the roll.

2. A machine having means for supporting a rotating roll with a rapidly travelling surface which changes in position with change in diameter of the roll and transfer of a web relative to the roll, a first zone along said roll surface exposed to personnel, a second danger zone along said roll surface to be protected, a movable guard member positioned adjacent said surface between said zones protecting said second zone, fluid pressure operated means for moving said guard member, means for supplying fluid under pressure to said pressure operated means, and control means operated by change in roll diameter connected to said fluid pressure supply means and controlling fluid delivery to said pressure operated means maintaining the guard in close guarding proximity with said surface as the roll changes in size.

3. In a winding machine having a winder drum for engaging a roll with a web being wound thereon, a guard beam extending along the roll ahead of the winder drum, fluid pressure operated means for positioning the guard beam relative to the roll surface, means moving as a function of the increase in roll diameter and providing a displacement signal, means converting said displacement signal to a control signal, and fluid pressure supply means delivering fluid to said fluid pressure operated means operated by said control signal means to give the guard a position in continued close guarding proximity to the surface of the roll.

4. In a winding machine having a winder drum for engaging a roll with a web being wound thereon, a guard beam extending along the roll ahead of the drum, a fluid pressure operated means for positioning the guard beam relative to the roll surface, means moving as a function of increase in roll diameter providing a displacement signal, a shaped cam driven by said moving means and having a surface shaped to produce a signal converting said displacement signal to a control signal which is a function of the movement of the power means required to position the guard beam in close proximate guarding relationship to the roll surface, and means operated by said control signal for supplying a variable pressure to said pressure operated means as a function of said con-

trol signal for positioning the guard beam and maintaining it in close proximate guarding relation to the roll.
